UNITED STATES PATENT OFFICE.

CHARLES T. MENZE, OF ST. LOUIS, MISSOURI, ASSIGNOR OF ONE-HALF TO
HENRY GERLITZ, OF SAME PLACE.

MEASURING-RECEPTACLE.

SPECIFICATION forming part of Letters Patent No. 479,151, dated July 19, 1892.

Application filed April 19, 1892. Serial No. 429,802. (No model.)

To all whom it may concern:

Be it known that I, CHARLES T. MENZE, of the city of St. Louis and State of Missouri, have invented certain new and useful Improvements in Measuring-Receptacles, of which the following is a full, clear, and exact description, reference being had to the accompanying drawings, forming a part hereof.

My invention relates to improvements in measuring-receptacles; and it consists in the novel arrangement and combination of parts, as will be more fully hereinafter described, and designated in the claims.

In the drawings, Figure 1 is the front elevation of my complete invention. Fig. 2 is a vertical section thereof taken through one of the spouts or chutes; and Fig. 3 is a side elevation of one of the spouts or chutes, especially showing its adjustable mechanism.

The object of my invention is to construct a device especially designed for the use of grocery-stores to prevent the repeated weighing of articles. I desire to state in this connection that my invention may be used for measuring coffee, sugar, tea, spices, soda, wheat, corn, oats, coal, and any solid where the lumps are not too large, and I may also extend the same principle for measuring liquids, such as molasses, oils, milk, &c.

I will give a further description of the important use and object of my invention in connection with the mechanical description thereof.

Referring to the drawings, 1 indicates the receptacle in which the article or articles to be weighed are placed. Said receptacle is provided with a detachable lid 2, with a bottom 3, and with a supplemental downwardly-inclined bottom 4, so as to facilitate the exit of the substance placed in said receptacle. Said

receptacle 1 is provided with an opening 5, which extends transversely across the front of the same, through which the substance finds an exit into the spouts located below the same. Said opening 5 is covered by an inclined exterior wall 6, which is secured to the receptacle in any suitable mechanical and artistical manner. Said opening 5 is provided with a bottom 7, and in said bottom 7 openings or holes are formed for the insertion and removal of cut-off valves.

The receptacle 1 is provided with a glass

plate 8, so that the interior contents of the receptacle may be observed.

In the construction as illustrated I provide the receptacle 1 with three chutes or spouts, 55 and beginning with the smallest they are respectively 9, 10, and 11, and said spouts or chutes 9, 10, and 11 are respectively provided with cut-off valves 12, 13, and 14. Said spouts 9, 10, and 11 are respectively provided with 60 glass plates 15, 16, and 17, so that the contents of said spouts may be observed. The spouts 9, 10, and 11 are respectively provided with right-angular perforated brackets 18, 19, and 20 for the purpose more fully 65 hereinafter described. The spouts or chutes 9, 10, and 11 are provided with vertically-adjustable sleeves or spouts 21, 22, and 23. Said vertically-adjustable sleeve or spout 21 fits snugly on and is inserted over the spout 70 9, and said sleeves 22 and 23 are similarly and respectively applied to the spouts 10 and 11.

The vertically-adjustable spouts or sleeves 21, 22, and 23 are respectively provided with outlet-valves 24, 25, and 26. 75

I will now proceed to describe the mechanism by which the sleeves 21, 22, and 23 are adjusted. The sleeves 21, 22, and 23 are respectively provided with perforated screw-threaded right-angular brackets 27, 28, and 80 29. Stationarily and revolvably mounted in the brackets 18, 19, and 20 are screw-threaded thumb-screws 30, and said thumb-screws are also mounted, or, more specifically, inserted, in the brackets 27, 28, and 29. It can be 85 readily perceived from this construction that the sleeves 21, 22, and 23 are adjustably united to the spouts 9, 10, and 11 by means of the aforesaid screw-threaded bolts 30. Said screw-threaded bolts 30 are provided with roughened heads 31, which answer as thumb-pieces for turning said bolts. By the proper manipulation of said bolts the sleeves 21, 22, and 23 may be adjusted as desired. 90

By applying the adjustable sleeves to the 95 spouts, as hereinbefore mentioned, a compartment or compartments 32 are formed, the cut-off valves forming the top of said compartment and the outlet-valves forming the bottom. 100

Referring to Fig. 2 for illustration, it can be readily perceived that by elevating or low-

ering either of the adjustable sleeves the cubical dimensions of the compartment 32 are varied—that is, increased or diminished.

I will now describe the operation and advantage of my improved measuring-receptacle. The receptacle 1 is filled with any desired substance, it being premised that the cut-off valves 12, 13, and 14 are pushed in and closed. For instance, if said receptacle is filled with 5 coffee, then take one pound of coffee and place it in compartment 32 and so adjust the sliding sleeve 21 that said pound exactly occupies the space of said compartment 32. We then have the cubical dimensions of a 10 pound of coffee and then in the future if it is desired to sell one pound of coffee it is only necessary to pull out the valve 12, let the compartment 32 be filled, then push in said valve, and you have a pound of coffee, and the same 15 may be exhausted by pulling out valves 24. It may be noted in this connection, or rather conceived, that the spout farthest to the right in Fig. 1 is adjusted to hold one pound, the spout adjacent to it two pounds, and the 20 spout located to the left three pounds, or the same may be so adjusted that they may hold any desired weight.

Having fully described my invention, what I claim is—

30 1. In a measuring-receptacle, the combination, with a spout provided at opposite sides with right-angular apertured brackets, of a

sleeve receiving said spout and provided with two oppositely-located brackets, the latter being in line with the brackets carried by the 35 spout and provided with screw-threaded apertures, and revoluble thumb-screws keyed to the spout-brackets and working in the sleeve-brackets, substantially as and for the purpose set forth.

2. A measuring-receptacle comprising a receptacle provided with an inclined bottom and with a transparent front, an opening formed in said receptacle above said inclined bottom, an outwardly-inclined face-plate for 45 said opening, spouts located below said opening, glass plates secured in said spouts, right-angular brackets also secured to the same, adjustable spouts or sleeves mounted on said first-mentioned spouts, right-angular screw-threaded brackets secured to said adjustable sleeves, cut-off valves located in said first-mentioned spouts and similar outlet-valves located in said adjustable sleeves, and screw-threaded bolts mounted in said brackets for 50 adjusting said adjustable sleeves or spouts, substantially as set forth.

In testimony whereof I affix my signature in presence of two witnesses.

CHARLES T. MENZE.
